Primary Examiner — Calvin E Vansant*Assistant Examiner* — Mark T. Philipp(74) *Attorney, Agent, or Firm* — Ewers IP Law PLLC;
Falk Ewers(57) **CLAIM**

The ornamental design for a compressor, as shown and described.

DESCRIPTION

FIG. 1 is a front elevation view of a compressor showing my new design;

FIG. 2 is a left side elevation view thereof;

FIG. 3 is a rear elevation view thereof;

FIG. 4 is a right side elevation view thereof;

FIG. 5 is a top plan view thereof;

FIG. 6 is a top and right side perspective view thereof; and,

FIG. 7 is a top and left side perspective view thereof.

The broken lines depict portions of the compressor in which the design is embodied that form no part of the claimed design.

1 Claim, 7 Drawing Sheets(56)
